UNITED STATES PATENT OFFICE.

JAMES T. ANDREW, OF MONTGOMERY, ALABAMA.

SAFETY APPLIANCE FOR RAILROAD-CARS.

No. 895,935.

Specification of Letters Patent. Patented Aug. 11, 1908.

Application filed May 25, 1907, Serial No. 375,685. Renewed December 31, 1907. Serial No. 408,748.

To all whom it may concern:

Be it known that I, JAMES T. ANDREW, a citizen of the United States, residing at Montgomery, in the county of Montgomery and State of Alabama, have invented certain new and useful Improvements in Safety Appliances for Railroad-Cars; and I do hereby declare the following to be a full, clear, and exact description of the invention, such as will enable others skilled in the art to which it appertains to make and use the same.

My invention relates to improvements in safety appliances for railroad cars, and is a specific improvement upon my prior patent No. 844,228, dated February 12, 1907.

The object of the present invention is to make specific improvements over the construction shown in said prior patent.

My invention is applicable not only to railway cars but also to electric cars of all kinds and also to locomotives, and it consists in the construction and combination of parts as hereinafter described and claimed.

In the accompanying drawings:—Figure 1 is a side view showing an ordinary passenger truck with my invention applied thereto. Fig. 2 is an end view of the same. Fig. 3 is a side elevation, partly in section, of a portion of the same on an enlarged scale, and Fig. 4 is a side elevation, partly in section, showing the manner of supporting the inner shoes of each pair.

a represents an ordinary passenger truck having the usual equalizer frame b and springs c and d. Bolted to the front and rear of the equalizer frame are brackets e and f, the journal boxes g being carried thereby and preferably made integral therewith, as shown in Fig. 3. These journal boxes play up and down between the inside bars h of an open frame, the outside bars of said frame being lettered i, the journal boxes being provided with the usual covers j.

Bolts k are fastened to the open frame which furnishes a guide for the journal box, and these bolts pass freely through slots in the corresponding bracket e. Each of the brackets e and f is provided with an extension. On each of these extensions is pivotally mounted a shoe m. For an ordinary form of truck there are eight of these shoes, one mounted inside and one outside of each wheel. These shoes are supported under ordinary conditions by springs n and are of the type mentioned in my former patent referred to above.

A chain such as o is connected to pins on each journal box and passes over one of the side rails of the truck, for the purpose of keeping the journal boxes in place if the axle should break close to the box, as sometimes happens.

p represents auxiliary beams for supporting the inner shoe of each pair. To these beams is bolted the upper semi-circular half of the casing q, the lower parts of said casing being attached to the upper parts by means of bolts r. This casing q extends from the inside of one wheel to the inside of the opposite wheel, so as to prevent the axle from dropping if it should break between the wheels. To each of the beams p is bolted a downwardly extending substantially triangular frame s, which carries at its lowest central point a boss t for the reception of the pin u carrying one of the inner shoes v. The pin u extends through both of said frames s and carries both of the inner shoes v. A V-shaped brace w is secured by a bolt to the casing q and surrounds said pin u, said brace w having projecting portions y against which the inner faces of the shoes v abut, the shoes being kept in position on said pin u by means of said enlarged portions y and cotter pins z passing through the rod or pin u.

Having thus described my invention, what I claim as new and desire to secure by Letters Patent of the United States is:—

1. In a safety appliance for cars and locomotives, the combination of a truck having an equalizer frame, brackets secured to said equalizer frame, each having a journal box thereon, a shoe pivotally supported on each of said brackets, and springs normally holding said shoes in a horizontal position, substantially as described.

2. In a safety appliance for cars and locomotives, the combination of a truck having an equalizer frame, brackets secured to said frame, each of said brackets having a journal box made integral therewith, guides for said journal boxes, a chain attached to each of said journal boxes and passing over a fixed portion of the truck, shoes, one of which is pivotally mounted on each of said brackets, and springs normally holding said shoes in a horizontal position, substantially as described.

3. In a safety appliance for cars and locomotives, the combination of a truck having an equalizer frame, supporting beams carried thereby, downwardly-extending frames sup-

ported by said truck, a casing surrounding the car axle bolted to said beams, a pin or rod supported by said frames, shoes pivotally mounted on said pins, and springs normally holding said shoes in their proper positions on said rods, substantially as described.

4. In a safety appliance for cars and locomotives, the combination of a truck, beams carried thereby and a triangular frame projecting downwardly and bolted to each beam, a casing surrounding the car axle, made of two parts bolted together, said casing being bolted to said beams, a pin or rod

passing through said frames, a shoe pivotally mounted on said rod near each extremity thereof, springs normally holding said shoes in a horizontal position, and a V-shaped brace attached to said casing and having its ends surrounding said rod, substantially as described.

In testimony whereof, I affix my signature, in presence of two witnesses.

JAMES T. ANDREW.
